SPOOL FOR CABLE, WIRE AND THE LIKE

Albert Storz, Pottstown, Pa., assignor to Alpha Wire Corporation, a division of Loral Corporation, Elizabeth, N.J.

Filed May 15, 1967, Ser. No. 7,108

Term of patent 14 years

(Cl. D41—1)

FIG. 1 is a perspective view of one side of the spool for cable, wire and the like and the interior of the opposite side while the side opposite is substantially the same as the side shown, and

FIG. 2 is an end view of the spool.

I claim:

The ornamental design for a spool for cable, wire and the like, substantially as shown and described.
